DESIGN FOR A TRANSPARENT SEWING MACHINE PRESSER FOOT

Viola Lains, Seattle, Wash.

Application July 28, 1942, Serial No. 107,731

Term of patent 14 years

To all whom it may concern:

Be it known that I, Viola Lains, a citizen of the United States of America, residing at Seattle, in the county of King and State of Washington, have invented a new, original, and ornamental Design for a Transparent Sewing Machine Presser Foot, of which the following is a specification, reference being had to the accompanying drawing, forming part thereof.

Figure 1 is a perspective view of a transparent

sewing machine presser foot, illustrating my new design.

Figure 2 is a top plan view of the same, Figure 3 is a front elevational view of the same, and Figure 4 is a longitudinal sectional view taken vertically through the same on line 4—4 of Figure 2.

I claim:

The ornamental design for a transparent sewing machine presser foot, substantially as shown.
